US0D1006014S

(12) **United States Design Patent** (10) **Patent No.:** **US D1,006,014 S**
(45) **Date of Patent:** **** Nov. 28, 2023**

(54) **SMART WATCH**

(71) Applicant: **Samsung Electronics Co., Ltd.**, Suwon-si (KR)

(72) Inventors: **Insik Chung**, Suwon-si (KR); **Juan Lee**, Suwon-si (KR); **Kenji Yamauchi**, Suwon-si (KR)

(73) Assignee: **SAMSUNG ELECTRONICS CO., LTD.**, Suwon-si (KR)

(**) Term: **15 Years**

(21) Appl. No.: **29/818,574**

(22) Filed: **Dec. 9, 2021**

(30) **Foreign Application Priority Data**

Jun. 30, 2021 (KR) 30-2021-0031082

(51) **LOC (14) Cl.** **14-02**

(52) **U.S. Cl.**

USPC **D14/344**

(57) **CLAIM**

The ornamental design for a smart watch, as shown and described.

DESCRIPTION

FIG. 1 is a front perspective view of a smart watch showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear perspective view thereof.

The dashed broken lines in the figures depict portions of the smart watch that form no part of the claimed design.

1 Claim, 8 Drawing Sheets
